US00D360102S

United States Patent [19]

Geissler et al.

[11] Patent Number: Des. 360,102

[45] Date of Patent: ** Jul. 11, 1995

[54] MICROWAVE CORN POPPER DEVICE

[75] Inventors: **Richard L. Geissler**, Chippewa Falls;
Roger L. Kelly, Eau Claire, both of Wis.

[73] Assignee: **National Presto Industries, Inc.**, Eau Claire, Wis.

[**] Term: 14 Years

[21] Appl. No.: 15,482

[22] Filed: Nov. 17, 1993

[52] U.S. Cl. D7/325; D7/323;
D7/500

[58] Field of Search D7/325, 500; 219/728,

[57] CLAIM

The ornamental design for a microwave corn popper device, as shown.

DESCRIPTION

FIG. 1 is a perspective view of a microwave corn popper device showing our new design;

FIG. 2 is a side elevational view thereof, all sides being identical;

FIG. 3 is a top plan view thereof;

FIG. 4 is a bottom plan view thereof, and,

FIG. 5 is a bottom plan view of a second embodiment of a microwave corn popper device, the perspective view, the side elevational view, and the top plan view being identical to that shown in FIGS. 1-3.
